GAME BOARD

Carl K. Corwin, Aliquippa, Pa.

Application November 22, 1950, Serial No. 13,101

Term of patent 3½ years

(Cl. D34—5)

To all whom it may concern:

Be it known that I, Carl K. Corwin, a citizen of the United States of America, residing at Aliquippa, in the county of Beaver, and State of Pennsylvania, have invented a new, original, and ornamental Design for Game Board, of which the following is a specification, reference being had to the accompanying drawing, forming part thereof.

The figure is a perspective view of a game board showing my new design.

The dominant features of my new design are shown in solid lines in the drawing.

I claim:

The ornamental design for a game board, as shown and described.

CARL K. CORWIN.
